MECHANICAL PENCIL WITH STEP-BY-STEP FEED

John B. Traylor, Denver, Colo.

Application April 24, 1945, Serial No. 590,035

6 Claims. (Cl. 120—17)

1

My invention relates to pencils and has particular reference to mechanically actuated pencils of the type in which a handle or holder is shaped to receive individual lengths of pencil leads to be fed from the interior of the pencil assembly as leads are consumed.

Various types of mechanically actuated pencil structures are in common use, such pencils usually comprising a handle or holder in which a length of separate lead is inserted, the holder having mechanism provided whereby a rotational movement of a portion of the handle relative to some other portion of the handle will cause a push rod device to engage the inner end of the length of pencil lead and force the same out through the pencil tip.

In other forms a ratchet mechanism actuated by a pressure exerted upon a portion of the pencil holder or handle is employed to project the lead from the pencil tip as it is consumed.

All of these forms of pencils require a ceasing of the writing activity of the user and some positive operation of a portion of the pencil in order to feed additional lead from the pencil tip, such operations invariably requiring the pencil to be shifted from its normal writing position in the hand in order that the lead feeding mechanism may be manipulated.

It is an object of my invention to provide a pencil construction of the general character set forth above, but in which the lead may be fed from the pencil tip while the pencil is still in a writing position in the hand of the user.

Another object of my invention is to provide a pencil construction of the character described wherein a sharp reciprocation or shaking of the pencil in a direction coincident with or parallel to the longitudinal axis of the pencil will accomplish a step by step feeding of the lead from the pencil tip.

Another object of my invention is to provide a pencil construction of the character set forth wherein a small weight is employed within the pencil handle adapted to be shaken by a reciprocatory motion of the pencil handle, the weight storing up a sufficient energy to actuate the lead feeding mechanism to feed the lead from the pencil tip.

Another object of my invention is to provide a pencil of the construction set forth in the preceding paragraph wherein at the end of the feeding motion the lead pushing mechanism will be locked against retraction of the lead as the user resumes writing with the pencil.

Other objects of my invention will be apparent

2

from a study of the following specifications, read in connection with the accompanying drawings, wherein

Fig. 1 is a vertical sectional view taken through a pencil construction embodying the principles of my invention.

Fig. 2 is a detailed fragmentary perspective view of the lead pushing and feeding mechanism and the normal position of the parts when the lead is in a writing position.

Fig. 3 is a perspective view similar to Fig. 2 and illustrating the position of the parts when a portion of the feeding mechanism is retracted ready to feed the lead forwardly in the pencil.

Fig. 4 is a perspective view similar to Fig. 3 illustrating the position of the parts during the intermediate step in the operation of feeding the lead forwardly.

Fig. 5 is a detailed transverse sectional view taken along line V—V of Fig. 1.

Referring to the drawings, I have illustrated a pencil construction comprising generally a tubular housing or handle 1 preferably constructed of metal or a similar material which will have the characteristic of substantial strength even though the walls of the tubular handle are made relatively thin so as to provide an inner chamber 2 of a substantial cross sectional area within the handle 1.

The forward end of the handle 1 is secured in a suitable manner, as indicated at 3, to a pencil tip structure 4 comprising an externally tapered member having a longitudinal bore 5 extending therethrough of approximately the same diameter as the diameter of a length of pencil lead 6 to be used in the pencil. The pencil tip 4 has a counter-bore, as indicated at 7, for the reception of a basket-like spring 8 adapted to engage the sides of the lead 6 to frictionally hold the same within the tip 4, but through which the lead may be fed by force exerted by the lead feeding mechanism hereinafter described.

The lead feeding mechanism comprises a fixed lead guide 9 comprising a substantially tubular member extending from a position immediately above the spring 8 to a position adjacent the rear end of the pencil where it may be engaged with a cup-like container 10 adapted to hold a supply of lengths of pencil lead. The lead guide 9 is shaped, as indicated most clearly in Figs. 2, 3 and 4, as a tube having an internal bore 11, conforming in diameter with the diameter of the leads to be used in the pencil but having a longitudinal slot 12 extending substantially through-

out its length, the slot having one of its sides

13 smooth, while the opposite side is formed with a plurality of regularly spaced downwardly directed ratchet teeth **14**.

Mounted within the bore **11** of the lead guide **9** is a push rod **15**, cylindrical in shape and having a diameter such that it will freely move up and down within the bore **11**. The push rod **15** has upon its upper end a head **16** comprising a pawl having a transverse cross-sectional shape of a segment of a circle projecting laterally from the circle defined by the push rod **15**, the width of the head **16** projected through the slot **12** being equal to the minimum space between the smooth edge **13** and the edge of the teeth **14** so that the head **16** may freely pass along the slot **12**.

Surrounding the lead guide **9** is a weight guide **17** constructed as a length of tubular member having a slot **18** extending longitudinally throughout its length, the slot **18**, like the slot **12**, being formed with one smooth edge **19** and a plurality of downwardly projecting teeth **20** upon the opposed edge, the teeth conforming in shape and depth with the teeth **14**. It will be observed, however, that the smooth edge **19** of the weight guide is disposed adjacent the toothed edge of the lead guide **9** and the teeth **20** on the weight guide are disposed adjacent the smooth edge of the slot **12** on the lead guide.

By referring particularly to Fig. 1 it will be noted that the overall length of the weight guide **17** is slightly less than the length of the lead guide **9** so that the weight guide is permitted a limited freedom of movement longitudinally along the lead guide **9**, the distance of such free movement being preferably a distance just slightly in excess of the longitudinal length of one of the teeth **20**, so that the weight guide may be retracted from its normal or lowermost position, as shown in Figs. 1 and 3, to an elevated position, as illustrated in Fig. 3, to present the next lowermost tooth **20** above the push rod head **16**.

To accomplish the reciprocatory movement of the weight guide **17**, I mount a tubular weight **21** loosely upon the weight guide **17** for free movement longitudinally along the weight guide, the weight guide being provided at spaced points along its length with stops or obstructions **22** and **23**.

I interpose between the tip and the weight guide **17**, a spring **24** indicated as being anchored at **25** in the tip and at **26** in the weight guide, the spring being illustrated as a helical spring under rotary tension so that the weight guide **17** is normally urged in a clockwise direction relative to the lead guide **9**, with the result that the teeth **20** are urged against the side of the push rod head **16** to engage this head while the head of the push rod is urged against the teeth **14** of the lead guide **9** to engage above the push rod head **16**.

Under the influence of the spring **24** the push rod, lead guide and weight guide assume the positions shown in Fig. 2 where it is apparent that the push rod **15** is prevented from any upward or retractive movement by the engagement of the teeth **14** with the head **16**.

Now if the pencil is given a longitudinal jolt or shake, the weight **21** will move up upon the weight guide **17** or pin until it strikes the pin or other obstruction **22**, the inertia of the weight causing the weight guide to be elevated through the short distance between the top of the weight guide and the container **10**. At this instant the parts will be in the position shown in Fig. 3 wherein the weight guide has been moved to an

elevated position, the teeth **20** rotating past the push rod head **16** by yielding of the spring **24** at a time when the push rod head is held against upward movement by its engagement with the teeth **14** on the lead guide **9**.

The descent of the weight **21** will result in the engagement by the weight of the pin or obstruction **23** to forcibly move the weight guide down to its original and normal position. During this movement of the weight guide the teeth **20** of the weight guide will engage the upper surface of the push rod head and will move the push rod down a distance equal to the normal spacing between the upper end of the weight guide and the container **10**, the push rod head ratcheting past the teeth **14** by the yielding action of the spring **24**.

Thus as the writer uses up the projecting portion of the lead **6** all that is necessary is to give the pencil a longitudinal shake or jolt and a new portion of the lead will be projected downwardly of the tube of the pencil, this process being repeated until all of the lead has been consumed, at which time the push rod **15** will be in its lowermost position.

The container **10** is rigidly secured to the lead guide **9** as by soldering or other suitable process, as indicated at **27**, so that the container may be rotated relative to the handle **1** and will rotate the lead guide relative to the handle and tip.

The container **10** is preferably formed with an open upper end which may be used to receive an eraser **28** to be covered by a cap **29** formed as a separate and removable piece, but by reason of its close fit upon the upper end of the container **10**, or by an interfitting of the cross sectional configurations given to the cap **29** and the upper end of the container **10**, rotation of the cap **29** will result in the rotation of the container **10**.

Thus when the piece of lead which has been in the lead guide has been completely consumed a new piece of lead may be inserted from the tip end of the pencil and the push rod **15** may be pressed back to its uppermost or original position by pressure exerted upon the incoming lead.

During this operation, however, the cap **29** is given a slight twist or lateral movement relative to the handle member **1** which will rotate the lead guide **19** relative to the weight guide **9**. Such rotation will free the push rod head **16** from

the notches **14**, while at the same time the head is freed from the notches **20**, and push rod **15** is free for a retractive movement along the slots **12** and **18** guided on each side of the head **16** by the smooth edges **13** and **19**. When the lead has

been completely inserted into the pencil a release of the cap **29** will permit the spring **24** to restore the lead guide and weight guide to their original relative rotational positions as shown in Fig. 2 and the pencil is again ready for use and for lead feeding by imparting a longitudinal shake or jolt to the assembly.

It would be apparent therefore that a writer using the pencil merely has to cease writing and raise his hand from the surface upon which he has been writing a sufficient distance to impart a sharp jerk to the pencil with the result that a fresh section of the lead will be projected out of the tip end of the pencil ready for the resumption of writing operations.

While I have shown and described the preferred embodiment of my invention, I do not desire to be limited to any of the details illustrated or described herein except as defined in the appended claims.

I claim:

1. In a pencil construction, a handle member, a lead guiding tip on one end of said handle through which a lead is fed to expose a short length outwardly of the tip, a lead guide extending longitudinally of said handle, a push rod slidably mounted in said lead guide and having a pawl extending laterally of said push rod, a longitudinally extending slot in said lead guide, through which said pawl extends, the material of the lead guide at one side of said slot being provided with a plurality of ratchet teeth engageable with said pawl, and a weight means mounted in said handle for free longitudinal movement along said handle for imparting an impact to said push rod upon a reciprocatory movement of the assembly to move said push rod and pawl to the next tooth in the direction of the movement of lead out to the tip of the pencil.

2. In a pencil construction, a handle member, a lead guiding tip on one end of said handle through which a lead is fed to expose a short length outwardly of the tip, a lead guide extending longitudinally of said handle, a push rod slidably mounted in said lead guide and having a pawl extending laterally of said push rod, a longitudinally extending slot in said lead guide through which said pawl extends, the material of the lead guide at one side of said slot defining a plurality of ratchet teeth engageable with said pawl, a second ratchet means in said handle including a plurality of downwardly directed ratchet teeth extending longitudinally of said handle, means mounting said ratchet means for a limited longitudinal movement in said handle, and a weight means associated with said ratchet means and actuated by a reciprocatory motion imparted to the assembly for causing said ratchet means to first move rearwardly from said tip to engage the next succeeding tooth thereon with the pawl and then to move forwardly toward the tip to press the push rod to a new forward position engageable with the next succeeding tooth on the lead guide to thereby feed a new portion of the lead from the pencil tip.

3. In a pencil construction, a handle member, a lead guiding tip on one end of said handle through which a lead is fed to expose a short length outwardly of the tip, a lead guide extending longitudinally of said handle, a push rod slidably mounted in said lead guide and having a pawl extending laterally of said push rod, a longitudinally extending slot in said lead guide through which said pawl extends, the material of the lead guide at one side of said slot defining a plurality of ratchet teeth engageable with said pawl, a second ratchet means in said handle including a plurality of downwardly directed ratchet teeth extending longitudinally of said handle, means mounting said ratchet means for a limited longitudinal movement in said handle, a weight means associated with said ratchet means and actuated by a reciprocatory motion imparted to the assembly for causing said ratchet means to first move rearwardly from said tip to engage the next succeeding tooth thereon with the pawl and then to move forwardly toward the tip to press the push rod to a new position engageable with the next succeeding tooth on the lead guide to thereby feed a new portion of the lead from the pencil tip, and a yieldable means normally urging said ratchet means and said lead guide to such relative rotational positions as will maintain said pawl engaged with the teeth on both the lead guide and the ratchet means.

70

75

4. In a pencil construction, a handle member, a lead guiding tip on one end of said handle through which a lead is fed to expose a short length outwardly of the tip, a lead guide extending longitudinally of said handle, a push rod slidably mounted in said lead guide and having a pawl extending laterally of said push rod, a longitudinally extending slot in said lead guide through which said pawl extends, the material of the lead guide at one side of said slot defining a plurality of ratchet teeth engageable with said pawl, a second ratchet means in said handle including a plurality of downwardly directed ratchet teeth extending longitudinally of said handle, means mounting said ratchet means for a limited longitudinal movement in said handle, a weight means associated with said ratchet means and actuated by a reciprocatory motion imparted to the assembly for causing said ratchet means to first move rearwardly from said tip to engage the next succeeding tooth thereon with the pawl and then to move forwardly toward the tip to press the push rod to a new forward position engageable with the next succeeding tooth on the lead guide to thereby feed a new portion of the lead from the pencil tip, and spring means interposed between said lead guide and said ratchet means for yieldably urging said ratchet means and lead guide to such rotatable position as will cause the teeth of both of said members to engage said pawl.

5. In a pencil construction, a handle member, a lead guiding tip on one end of said handle through which a lead is fed to expose a short length outwardly of the tip, a lead guide extending longitudinally of said handle, a push rod slidably mounted in said lead guide and having a pawl extending laterally of said push rod, a longitudinally extending slot in said lead guide through which said pawl extends, the material of the lead guide at one side of said slot defining a plurality of ratchet teeth engageable with said pawl, a second ratchet means in said handle including a plurality of downwardly directed ratchet teeth extending longitudinally of said handle, means mounting said ratchet means for a limited longitudinal movement in said handle, a weight means associated with said ratchet means and actuated by a reciprocatory motion imparted to the assembly for causing said ratchet means to first move rearwardly from said tip to engage the next succeeding tooth thereon with the pawl and then to move forwardly toward the tip to press the push rod to a new forward position engageable with the next succeeding tooth on the lead guide to thereby feed a new portion of the lead from the pencil tip, and a yieldable means normally urging said ratchet means and said lead guide to such relative rotational positions as will maintain said pawl engaged with the teeth on both the lead guide and the ratchet means, and means for rotating said lead guide and ratchet means to another position disengaging the teeth of both of said members from said pawl to permit retraction of said pawl and push rod.

6. A pencil construction comprising a hollow handle member, a stationary tubular member disposed therein for guiding lead and having a longitudinal slot therein that is provided with a continuous series of notches on one edge, a lead advancing pawl disposed within said guide and projecting through said slot and having means to engage said notches to prevent its movement in one direction, a movable member disposed

about said guide for movement therealong and having a series of notches for engaging said pawl that are substantially the same size as the guide notches and preventing movement similarly to the guide notches, and means limiting the movement of the movable member along the lead guide to a distance not less than the length of a notch and not more than a distance just slightly less than the length of two notches, whereby reciprocation of the movable member advances the pawl not more than one notch for each reciprocation.
